UNITED STATES PATENT OFFICE.

JAMES H. MELICK, OF ALBANY, NEW YORK.

THRASHING-MACHINE.

SPECIFICATION forming part of Letters Patent No. 425,444, dated April 15, 1890.

Application filed August 27, 1886. Renewed March 18, 1890. Serial No. 344,422. (No model.)

To all whom it may concern:

Be it known that I, JAMES H. MELICK, a citizen of the United States, residing at Albany, in the county of Albany and State of New York, have invented certain new and useful Improvements in Thrashing - Machines, of which the following is a specification.

My invention relates to improvements in the class of thrashing-machines illustrated and described in Letters Patent No. 261,167, granted to me July 18, 1882; and it consists of the combinations of parts hereinafter particularly described, and specifically set forth in the claims.

15 The objects of my invention are, first, to provide in a thrashing-machine, and in combination with the main frame and a thrashing-cylinder and its concave fixed within said frame, a detachable frame containing a 20 thrashing-cylinder and a coacting concave and a driving-wheel which can be made to operate either of said thrashing-cylinders without operating the other; secondly, to provide several specific combinations of devices, by 25 means of which new and advantageous results can be obtained in a thrashing-machine, which employs with a main frame, containing a thrashing-cylinder and coacting concave straw-conveyer, a detachable frame containing 30 a second thrashing-cylinder and coacting concave. I attain these objects by the combinations of devices illustrated in the accompanying drawings, forming a part of this specification, in which—

35 Figure 1 is a plan view of a thrashing-machine embodying the improvements with top covers removed from over the upper cylinder. Fig. 2 is a side elevation of the same. Fig. 3 is a sectional elevation of the same. Fig. 4 is a front end elevation with the upper feed-table removed. Fig. 5 is a cross-sectional view taken at line 1 in Fig. 3.

In the drawings, A A represent the main frame of the machine, which contains and 45 holds the operating parts.

B B is a folding or detachable frame, jointed to the forward upper portion of the main frame A A by means of suitable hinges a a, connecting the rear side portion of this folding frame 50 with the upper side of the main frame, so that the former can be turned up from position

shown by full lines in Fig. 2 to that shown by dotted lines in the same figure and the reverse. Binding-bolts b, or equivalent hooks or clips, (not shown,) are employed to hold this 55 folding or detachable frame securely joined with the main frame when the cylinder in the former is being operated. By loosening these bolts or their equivalent devices this frame B B can be turned up and back on its hinges 60 a a at pleasure and be folded top side down on the deck of the main frame A A. This folding or detachable frame is made to contain one of the two thrashing-cylinders and its concave and the feed-table of the cylinder 65 and other adjuncts.

C is a spike-cylinder, sometimes called the "short-straw" cylinder, which is mounted on a shaft supported in suitable bearings on frame B B, and C' is a suitable spike-cylinder 70 concave, which is supported in this folding or detachable frame beneath spike-cylinder C. This concave is provided with any suitable adjusting device by which it can be set nearer to or away from the cylinder, as may be preferred.

D is a feed-table suitably arranged and connected with the detachable or folding frame B B and in front of cylinder C, so that the operator can conveniently feed the grain to 80 the latter. This feed-table is preferably detachable from frame B.

E is a rubbing-cylinder, sometimes called a "long-straw" cylinder, which is mounted on a shaft, which is supported in suitable bearings attached to the main frame. This cylinder is relatively below cylinder C, and also rearward of the same, as shown, and is provided with a rubbing-concave E', which is suitably supported at its ends from the sides 90 of the main frame.

In my patent referred to the upper cylinder is situated rearward of the lower cylinder, and the straw and grain are delivered from the former to the separator at a point relatively at a considerable distance rearward of the forward end of the sieve-shoe, so that the blast from the fan through the sieve-shoe will not in all cases act as effectively as desirable, especially when operating with grain 100 in which the straw is heavy and well loaded. In my present improvement the upper cylin-

der is relatively forward of the lower cylinder, so that the thrashed straw and grain will be delivered in a direction over the lower cylinder and in front of the same, and on the 5 front end of the separator and relatively over the forward end of the sieve-shoe, so that the blast from the fan, passing through the sieve-shoe, will act effectively with all kinds and conditions of straw and grain.

10 In my former patent the rubbing-cylinder is arranged relatively above the spike-cylinder, and also relatively at a considerable distance above the plane of the separating and conveying mechanism, so that the long straw 15 is delivered from the rubbing-cylinder at an altitude above the straw-conveying mechanism, which necessitates a considerable distance of fall of the straw before lodging on the conveyer and separator, so that in some 20 cases the heavier ends of the straw would reach the conveyer before the lighter ends, and thereby cause an uneven lay of the straw. In my present improvements the rubbing-cylinder is in situation below the spike-cylinder and on such a plane that its concave E' 25 is but a short distance above the plane of the forward or receiving end of the separator and conveyer, so that when the straw is moved in its delivery from the cylinder horizontally 30 rearward it will at once be delivered on the conveying and separating mechanism without falling to any great distance, and thereby cause the straw to be uniformly about at right angles to the line of direction of rearward movement of the straw when it drops 35 on the conveying mechanism.

In my former patent referred to the spike or short-straw cylinder is situated relatively rearward and above the rubbing-cylinder and 40 at such a distance forward of the conveying mechanism as to necessitate the use of a grain-board between said cylinder and the conveyer, while at the same time the concave is shown to be in situation above its cylinder, 45 so that when the spike-cylinder is revolved the centrifugal force of the same dashes the straw and grain downwardly with considerable force on this grain-board, to be moved therefrom by the blast incidental with the 50 rapid revolution of the cylinder. In my present invention the spike-cylinder is relatively above and rearward of the rubbing-cylinder, with its concave C' arranged at its lower side, so that the centrifugal force of the revolving 55 cylinder, together with the blast therefrom, will toss the straw and grain slightly upward and rearwardly over the rubbing-cylinder to fall clear of the same on the moving conveying and separating mechanism for being 60 immediately operated in the most effective manner.

F is a fan-blower situated below the two thrashing-cylinders, and revolved by any suitable bands and pulleys in the manner generally practiced. In the discharge end of this 65 blower are arranged a series of air-valves v, which can be variously set for regulating the

air-currents passing into and through the sieve-shoes.

G and G' are vibrating shoes, the lower one 70 G containing the sieves suitably arranged in relation to each other and at angles suitable for effecting good operations with the grain to be cleaned. The upper shoe feeds into the lower shoe in the usual manner. These 75 shoes are arranged one above the other, and are supported, so as to be alternately shaken in opposite directions, by levers e and hangers e', (substantially as shown and described in Letters Patent No. 277,565, granted to me 8c May 15, 1883.) This shaking motion can be communicated to these shoes through suitable revolving eccentrics or cranks operating the pitman d, pivoted with the upper shoe G', when motion will be communicated from this 85 upper shoe through the levers and hangers e e' to the lower shoe G.

H is a reciprocating inclined grain-board, which is suspended within the sides of the machine and rearward of the thrashing-cylinders by suitable hangers f f'. The lower and front end of this grain-board is so arranged over the upper shoe G' as to discharge into the same at all times while said shoe and grain-board are being reversely vibrated. 95

In my patent referred to, No. 261,167, the grain-board is operated by a pitman and eccentric independently of the shoe beneath, which latter is shown to be operated by another pitman and eccentric. In my present 100 invention I dispense with the use of two pitmen and eccentrics and their necessary adjuncts for giving to them motion for operating the grain-board and shoe reversely and simultaneously, and employ but one set of eccentrics and pitmen, as already described as giving motion to shoe G', and by the vibrating movement of said shoe, operating through suitable mechanism provided, the said grain-board will be operated simultaneously with 105 said shoe, but in reverse directions. In this invention the mechanism employed consists of the arms g g, fixed to the sides of shoe G' and projected rearward of the same, and pivoted levers h, connected each at one end with 110 arms g by connecting-bars I and their opposite ends with the grain-board H by connecting bar or pitman j. With these devices between the upper shoe G' and grain-board H the movements of the latter will be communicated to the former, but in reversed directions, and at the same time the motion from 115 this upper shoe is communicated to the lower shoe G also in reversed directions. With these devices the two shoes G G' and grain-board H will be vibrated, as above described, without any jarring of the machine, so that 120 the grain falling on board H will be conveyed directly into the upper shoe in a scattering manner, and pass thence into the lower shoe, 125 to be thoroughly cleaned by the combined operations of the wind-currents and the agitation of the said shoes and grain-board.

K K are a series of agitating-conveyers ar-

ranged in an inclined position above the reciprocating grain-board H. Each of these conveyers is made a duplicate of the other, and consists of a pair of parallel bars k k, a series of transversely-arranged slats l l, and detent-pegs m m, as shown in Figs. 1 and 3. The forward and lower ends of these agitating-conveyers are connected with the multiplex crank-shaft L, in which each crank n is set opposite to its neighboring ones, and their rear ends are supported clear of the floor of the grain-board H, and are provided with mechanism by which said rear ends will be alternately raised and depressed as these conveyers are vibrated endwise in alternate directions, and in such a manner that their rear ends will be depressed when their front ends are raised, and the reversals be simultaneously effected. These agitating-conveyers are not the invention of myself. When the crank-shaft L is revolved, every other one of these agitating-conveyers will be moved endwise forwardly at the same time their front ends are being thrown downwardly, while the others in the series will be moved endwise rearwardly, with their front ends at the same time being thrown upwardly, and with this manner of movement of the two series of agitating-conveyers and the wind-currents passing upwardly and along the upper side of the bottom of the grain-board H the straw thrown rearwardly from the cylinders (as either is used) on these conveyers will be made to travel progressively rearward to a final discharge at the end of the machine, and in this passage of the straw the grain will be shaken out of the thrashed straw by the repeated and rapid alternate tossing and falling of the straw, while the straw will be held from sliding forward by the detent-pegs m m of one series of conveyers holding with the straw while those of the other series are being lowered and drawn away from the same.

M is a platform suitably supported from the frame of the machine and relatively in front of the lower thrashing-cylinder and past its ends, and on a plane so as to adapt it for use as a feed-table to that cylinder. In Fig. 1 this platform is shown by full and dotted lines to be below feed-table D and to extend across from side to side of the machine. It is also shown in the same figure to be held in situation for use as a feed-table by means of the hasps m' m', secured to the rearward portion of said platform and engaging with staples fastened in the adjoining cross-bar a' and secured by a cross-pin n'; yet it is evident this platform can be held from being moved away from this lower thrashing-cylinder by means of suitable hooks and eyes, or by bolts or other well-known holding devices, which will retain it in place, so as to admit it to be used as a feed-table to the said lower cylinder. This platform M can be extended forward and away from the lower thrashing-cylinder, so as to be in situation in relation to the feed-table D of the upper thrashing-

cylinder C, that it can serve as a floor on which the operator can stand when feeding grain to said upper cylinder. This extension or withdrawal of the said platform M can be effected by disconnecting it from cross-bar a' by disengaging their fastenings m' n' and moving the platform forward to dotted lines M' in Fig. 1.

N is a second platform, situated below the plane of platform M, for use of the operator as a standing-floor when platform M is being used as a feed-table to the lower cylinder E. This platform N is shown in Fig. 1 to have a jointed connection with the frame of the machine and held in position by chain n² with a side rail of said platform and a suitable hook secured to a stationary part of the frame of the machine. By means of this jointed connection of platform N with the frame of the machine the former can be folded upwardly when not in use or when the machine is being transported or stored.

P is a grain-board arranged below lower cylinder, concave E' and between the same and the front end of the upper shoe G', so as to conduct the grain falling from the lower concave (or upper concave) into said shoe.

Any suitable system of band-wheels, pulleys, and belts can be employed to give motion and speed to the respective moving parts; yet I prefer to drive the different parts from driving-wheel Q, substantially as illustrated by full and dotted lines in Figs. 1, 2, and 3. In this system illustrated the driving-wheel Q gives motion to the upper cylinder C through band q and pulley R, and also gives motion to lower cylinder E through band r and pulley S. The fan is driven by pulley T and band t from pulley U, while the multiplex crank L is revolved by band-wheel V, band u, and pulley W. The eccentrics c, operating-pitmen d, which give motion to shoe G', are revolved by driving-wheel Q, though it can be revolved by a pulley secured to the eccentric shaft and actuated by a driving pulley or wheel secured to any other suitable shaft. When upper cylinder C is used, its pulley R will be connected with drive-wheel Q, while pulley S of the lower cylinder E will be disconnected from said drive-wheel; but when the lower cylinder is used its pulley S will be connected with drive-wheel Q, while the pulley of cylinder C will be disconnected. When either of said two cylinders is used, the other revolving parts of the machine will each be driven through their respective pulleys and bands.

When wheat, oats, barley, or other short-straw grain is to be thrashed, proper sieves will be suitably arranged within shoe G, and pulley R of upper cylinder C will be connected with drive-wheel Q by bands q, while lower cylinder E will be allowed to be idle. The operator, standing on platform M, will feed the grain from platform D to between cylinder C and its concave C', when the cylinder, revolving in proper direction, will

thrash the grain and throw its parts rearwardly over the lower cylinder E to such a distance as to deliver it clear of the cylinder on the front and lower end of the separator 5 and conveyer K, when this mechanism will in its operations knock out from the straw the loosened grain and carry the straw rearward to be discharged over the rear end of the machine, while the grain will fall down 10 on the respective grain-boards O and P and reciprocating grain-board H and be delivered from them into the shoes G G' to be properly winnowed. In the time these different operations are being had the blast from the fan 15 will be operating on the grain passing through the shoes and their sieves, and a portion of this blast will with some degree of force rise upward through the separating and conveying mechanism K and prevent the straw from 20 lying heavy or dead on the same.

When rye or long-straw grain is to be thrashed, band q will be thrown off pulley R of cylinder C, and band r will be made to connect the driving-wheel Q with pulley S of cylinder E, and binding device b will be loosened and the detachable or folding frame B, containing cylinder C and concave C', will be turned up and back on the deck of the rearward portion of the machine, as indicated by 25 dotted lines in Fig. 2. Before folding frame B up and on the deck of the machine the platform D can be constructed and secured to said frame so as to be removable from it, if preferred. Should the machine be in a situation 30 which will not admit of the turning up and back of the said frame, the pins or pivot-bolts of the hinges a can be readily removed, when the said frame and cylinder and its adjuncts can be readily detached and moved to any 35 convenient place. The operator will stand on platform N and feed the grain from platform M to between cylinder E and its concave E', when the thrashed straw will be carried rearwardly and delivered on the lower 40 45 and front end of the separator and conveying mechanism K K to be operated with, as above stated, while the grain will be conducted by the respective grain-boards into the shoes G G' and be winnowed in the usual 50 manner.

By my above-described improvements I provide in the same machine two independently-operating thrashing-cylinders, one of which will operate as a long-straw or rubbing 55 cylinder to thrash and deliver the straw directly on or to the separating-conveyer to be cleaned and delivered free from grain in condition to be bunched or formed into bundles, while the other cylinder will be a short-straw

or spiked cylinder, which can be removed at 60 will from over the lower cylinder to permit operations with the same and be readily returned in place to prevent operations with the lower cylinder, while it will itself be in 65 situation for thrashing grain and delivering its straw directly to the same separator to be cleaned and delivered from the separator or conveyer for bailing. The shaft of cylinder C can be made sectional, with the main portion or middle section of the same supported in 70 suitable bearings from folding frame B, while the end sections or portions can be supported in suitable bearings from frame A, and be connected with the main or middle section of the shaft by suitable sleeves or by universal 75 joints, as may be preferred.

Having described my invention, what I claim, and desire to secure by Letters Patent, is—

1. In a thrashing-machine, the combination, 80 with the main frame and a thrashing-cylinder E and its coacting concave E', permanently arranged within said frame, of the detachable frame B B above the plane of the cylinder in the main frame, a thrashing-cylinder C and its coacting concave C', contained within said detachable frame, and a driving-wheel operating at will either of said cylinders without operating the other, substantially as and for the purposes set forth. 90

2. In a thrashing-machine, the combination, 85 with the main frame, a thrashing-cylinder E and its coacting concave E', and a winnowing mechanism, all permanently arranged with said main frame, of the detachable frame B B above the plane of the cylinder in the main frame and a thrashing-cylinder R and its coacting concave R' in said frame, a driving-wheel which can operate at the will of an attendant either of said cylinders without 100 operating the other, and the grain-boards O and P, substantially as and for the purposes set forth. 105

3. In a thrashing-machine, the combination, 110 with the extensible feed-table M, leading to a thrashing-cylinder permanently secured within the main frame, of the detachable frame B B, thrashing-cylinder C and its concave, feed-table D, leading to the cylinder in said detachable frame, and grain-boards O 110 and P, communicating with the winnowing mechanism, substantially as and for the purposes set forth.

JAMES H. MELICK.
